E. E. YAXLEY

ELECTRIC SWITCH

Filed Aug. 18, 1923

Inventor:
Ernest E. Yaxley
By G. L. Bragg Atty.

UNITED STATES PATENT OFFICE.

ERNEST E. YAXLEY, OF CHICAGO, ILLINOIS, ASSIGNOR OF ONE-HALF TO CARTER RADIO COMPANY, OF CHICAGO, ILLINOIS, A CORPORATION OF ILLINOIS, AND ONE-HALF TO YAXLEY MANUFACTURING COMPANY, OF CHICAGO, ILLINOIS, A CORPORATION OF ILLINOIS.

ELECTRIC SWITCH.

Application filed August 18, 1923. Serial No. 658,173.

To all whom it may concern:

Be it known that I, ERNEST E. YAXLEY, a citizen of the United States, residing at Chicago, in the county of Cook and State 5 of Illinois, have invented a certain new and useful Improvement in Electric Switches, of which the following is a full, clear, concise, and exact description.

My invention relates to electric switches 10 and has several objects and advantages in view.

In accordance with one feature of the invention the range of movement of the switch arm is regulable by means of an abutment 15 whose position may be changed to different parts of the path of movement of the switch arm for the purpose.

In accordance with another feature of the invention the switch arm and the contacts are 20 so constructed and related that the switch arm does not snap or settle while passing from one contact to another, but only after having fully left one contact and when about reaching the position in which it fully engages a 25 succeeding contact. In carrying out this feature of the invention adjacent contacts are provided with ridges at their adjacent sides. The contacting end of the switch arm is wider than the spaces between these ridges, 30 where adjacent, so that the switch arm will not snap until it has left both ridges, thereby indicating to the user when the switch arm has been brought to a new functioning position.

35 The invention also has another feature the provision of means for ensuring good electrical connection between a rod or shaft and a circuit continuing arm with respect to which the shaft is rotatable and which engages an end of said shaft. In carrying out 40 this feature of the invention a flexible connection is carried by and electrically connected at one end with said arm and is mechanically and electrically assembled with 45 said shaft at its other end.

The invention will be more fully explained by reference to the accompanying drawing in which Fig. 1 is a front view of a 50 switch as it is preferably constructed; Fig. 2 is a sectional view on line 2—2 of Fig. 1; Fig. 3 is a sectional view on line 3—3 of Fig. 1; Fig. 4 is a perspective view illustrating parts of the structure in separated

relation; Fig. 5 is a perspective view illustrating the assembly of the shaft and the 55 flexible connection carried by the arm that engages an end of the shaft; and Fig. 6 is a sectional view on line 6—6 of Fig. 5.

Like parts are indicated by similar characters of reference throughout the different 60 figures.

The switch mounting 1 may be in the form of a board or plate of insulation having an aperture therethrough which receives a bearing 2 formed with a shoulder or flange 65 3 upon one end and threaded at its other. A sleeve 4 is screwed upon the threaded portion of the bearing, and has a shoulder or flange 5 at its outer end. The mounting board 1 is clamped between the flanges 3 70 and 5. A disc 6 of metal or other suitable material is clamped between the flange 3 and the board 1. A disc 7 of insulation is assembled with the disc 6 by screws 8, 8'.

An arcuate row of contacts 9 is concentric with the cylindrical bore of the bearing 2. A spring contact arm or wiper 10 is fixedly carried upon a rod or shaft 11 which is journaled in the bearing 2, the outer or contacting end of this arm sweeping over the 75 contacts. A knob 12 is fixed upon the shaft by means of a set screw 13. The contacts 9 may be complementary to a common contact terminal 14 which may be in the form of an angular arm assembled by means of 80 screws 15 with the angular continuation 16 of the disc 6. The contact 14 presses upon one end of the rod or shaft 11 as this shaft and the contact arm 10 thereon are turned to bring this contact arm into engagement with 85 a selected contact. As illustrated the contact 14 and shaft 11 include the switch in circuit. A flexible conductor 17 is employed to ensure the continuity of the circuit portion established by the arm 14 and shaft 11, 90 this conductor being fixed mechanically and electrically assembled. Said conductor is preferably in the form of a light coiled spring carried upon the contact 14 by being assembled therewith by means of a screw or 95 bolt 18. The other end of said conductor is "staked" into mechanical and electrical assembly with the shaft 11 as indicated in Figs. 5 and 6.

Each contact 9 is assembled with its 100 mounting or support 7 by means of ears 9'

formed upon the contacts and passing through openings in the support 7 and clinched upon the back thereof.

The contacts 9 are provided with ridges 5 where these contacts are most adjacent, these ridges being in the arc of movement of the contacting end of the arm or wiper 10. For convenience of manufacture these ridges are circular as indicated at 9². The contacting 10 end of the spring arm or wiper 10 has a contacting portion 10 pressed thiercfrom that makes the contacting portion of the arm broader than the spaces between the adjacent ridges. In this way the contact arm 15 will not drop from the plane of the adjacent ridges until it has cleared both of these ridges. The user will know whether the switch arm is bridging two contacts or is in engagement with only one, as the noise 20 or click arises only when the latter is the case. The width of the contacting arm at its portion 10' is less than the diameter of the circles surrounded by the ridges 9² so that the contact arm may be held in full 25 engagement with the selected contact.

The maximum range of travel of the switch arm is coextensive with the row of contacts and is defined by the abutment 19 formed integrally from the same piece of 30 metal and held in place by the screw 8'. The range of movement of the arm may be shortened to exclude some of the contacts. To this end I employ an adjustable abutment 20, preferably of T shape. The 35 stem of the abutment is insertible through openings 2 through which the ears 9' are preferably passed, these openings located in different functioning positions of the switch arm and which openings are preferably 40 located between the contacts. When the abutment has been fully inserted within the selected opening, the parts are assembled so that the board 1 will engage the T head to keep the abutment in place; with the 45 stem thereof crossing the plane of movement of the switch arm.

Changes may be made without departure from the spirit of my invention.

I claim:

50 1. An electric switch structure including a row of contacts; a switch arm that is movable with respect to the row of contacts along the same; and an abutment with which said arm is engageable to limit the range 55 of movement of the arm with respect to the row of contacts, the switch structure and abutment being formed to enable their assembly at each of a plurality of different operative positions of the switch arm with 60 the abutment in functioning position.

2. An electric switch structure including a row of contacts; a switch arm that is movable with respect to the row of con-

tacts along the same; a mounting for said contacts formed with openings at different 65 operative positions of the switch arm; and an abutment with which said arm is engageable and receivable in any of said openings which are positioned to place the abutment in functioning position. 70

3. An electric switch structure including a row of contacts; a switch arm that is movable with respect to the row of contacts along the same; a mounting for said contacts having the contacts upon one of its 75 sides and formed with openings at different operative positions of the switch arm; and a T shaped abutment whose head is upon the other side of said mounting and whose stem is receivable in either of said openings and 80 is of a length to project into the path of relative movement of the arm and contacts.

4. An electric switch structure including a row of contacts; a switch arm that is movable with respect to the row of contacts 85 along the same; a mounting for said contacts having the contacts upon one of its sides and formed with openings at different operative positions of the switch arm; an abutment having a head and a stem, the stem 90 being receivable in any of said openings in position to be engaged by said switch arm; and a mounting for the switch structure positioned to engage the head of the abutment and hold the abutment in functioning 95 position.

5. An electric switch structure including a row of contacts; a switch arm that is movable with respect to the row of contacts along the same; a mounting for said contacts having the contacts upon one of its sides and formed with openings at different operative positions of the switch arm; and an abutment having angularly related 100 branches, one of which is upon the other side 105 of said mounting and the other of which is receivable in either of said openings and is of a length to project into the path of relative movement of the arm and contacts.

6. An electric switch structure including a 110 row of contacts; a switch arm that is movable with respect to the row of contacts along the same; a mounting for said contacts having the contacts upon one of its sides and formed with openings at different 115 operative positions of the switch arm; an abutment receivable in any of said openings and there engageable by the switch arm; and a mounting for the switch structure positioned to engage the abutment and hold 120 it in functioning position.

In witness whereof, I hereunto subscribe my name this 15th day of August, A. D., 1923.

ERNEST E. YAXLEY.
